F. C. HAMMAR,
PROTECTING DEVICE FOR THE EDGE OF BUTCHERS' KNIVES,
APPLICATION FILED JULY 3, 1922.

1,426,184.

Patented Aug. 15, 1922.

UNITED STATES PATENT OFFICE.

FRITIOF CORNELIUS HAMMAR, OF GOTTFENBORG, SWEDEN.

PROTECTING DEVICE FOR THE EDGE OF BUTCHERS' KNIVES.

1,426,184.

Specification of Letters Patent. Patented Aug. 15, 1922.

Application filed July 3, 1922. Serial No. 572,667.

To all whom it may concern:

Be it known that I, FRITIOF CORNELIUS HAMMAR, subject of the King of Sweden, residing at No. 30 Linnégatan, Gottenborg, 5 Sweden, have invented certain new and useful Improvements in and Relating to Protecting Devices for the Edge of Butchers' Knives, of which the following is a specification.

10 The present invention relates to protecting devices for the sharp edge of butchers' knives and particularly to such devices, in which the edge protecting member is held in proper position to the knife-blade by 15 means of a pin or the like, passing through holes in the knife-blade as well as in the edge protecting member.

10 The invention has for its principal object to provide an edge protecting device of the 20 class mentioned, which will enable an easy removing of the protecting member off from the knife-blade when the blade is to be ground.

Other objects of the invention will be 25 made clear by the following description.

The invention is characterized broadly therein, that either the hole provided in the edge protecting member or the corresponding hole in the knife-blade has such a shape 30 in relation to the pin cooperating with said holes, that when the protecting member is swung out about said pin from its operative position to have the edge of the knife-blade free for sharpening said pin remains stationary in relation to the knife-blade or to the protecting member as the case may be but is revolved in relation to the opposite member. Besides that the pin bears against the outer side of the last mentioned member 35 by means of a head of such a shape and size in relation to the hole in said member, that, since the edge protecting member has been swung to a certain angle to the knife-blade, the head of the pin can be pulled 40 out through said hole, so that the protecting member becomes released from the blade.

Referring now to the drawing illustrating one embodiment of the invention Fig. 1 shows the knife with the protecting member 50 in side elevation, Fig. 2 a portion of the knife-blade with the edge protecting member in position to be removed from the blade, Fig. 3 a portion of the knife-blade looked at from a side opposite to the side shown in 55 Fig. 1, Fig. 4 a section on the line A—A in

Fig. 1, Fig. 5 a view of a detail and Fig. 6 a section on the line B—B in Fig. 1.

In the drawing 1 denotes a knife-blade, which in ordinary way by means of screws 2 is fastened to the handle 3. To the one flat side of the knife-blade 1 there is attached an edge protecting member 4 such, that when in operative position (Fig. 1) said member leaves only a narrow rim of the edge of the blade uncovered. According to the present invention the knife-blade 1 adjacent to its outer end is provided with an oblong hole 6 and the edge protecting member with a corresponding hole 8 of a similar shape and forming an angle to the 70 hole 6. To the edge protecting member 4 there is by means of a screw 7 fastened a pin or bolt 9, which passes through the holes 6 and 8 and is formed with an oblong head 10 of such a size, that, when turned into a proper position, the head can pass through the hole 6 and after being rotated some quarter of a turn can be disposed transversely across the hole 6 on the side of the 75 blade 1 opposite to the edge protecting member 4, as shown in Figs. 3 and 4, thereby securing the member 4 to the knife-blade 1. Due to the fact, that the length direction of the hole 8 is disposed somewhat perpendicularly to the edge of the knife, the edge protecting member 4 can be withdrawn from the edge 5 inwardly upon the blade when the edge has been worn off to a certain extent and consequently the edge protecting member always can be adjusted to assume a 80 proper position in a suitable distance apart from the edge. The pin 9 is provided with a portion 11 of somewhat the same width as the hole 6, which portion projects into the hole 6 such, that when the member 4 is 85 swung about the screw 7, also the pin 9 with the head 10 will be turned the same angle. Between the head 12 of the screw 7, which head is provided with a notch 13 in order to enable the revolving of the screw by means 90 of a screw-driver or the like, and the member 4 there is provided a washer 14 with a larger diameter than the width of the hole 8 to prevent the screw head from passing through the hole 8.

100 The opposite end of the edge protecting member 4 as shown in Fig. 1 is disposed in a recess 15 in the handle 3 and is retained in this position by means of a spring 16 fastened to the handle, in which position 105 110

said end of the member 4 bears against the rim of a disc 17, which is fastened eccentrically to a pin 18 passing through the handle 3 and the recess 15 (see Fig. 6).

5 The device operates as follows:

When the edge protecting member 1 is to be removed in order to enable the grinding of the knife-edge, said member is swung from the operative position shown in Fig. 10 1 some 90 degrees into the position shown in Fig. 2. The head 10 of the pin 9, which in the first mentioned position of the member 4 assumes the position shown in Fig. 3 thereby securing the edge protecting member 15 to the knife-blade, because of the portion 11 projecting into the hole 8 of the member 4 partakes in the said movement of the member 4, so that the head 10 in the position of the member 4 shown in Fig. 2 is positioned straight before the hole 6 in the knife-blade. In such a position the head 10 can be passed through the hole 6 and thus the member 4 easily removed. Since the grinding of the knife-blade has been finished 25 the edge protecting member is placed in position on the blade in an opposite order and finally is swung to the operative position according to Figs. 1 and 3.

When the knife-blade by the grinding 30 has been worn off in certain degree the member 4 is pushed farther in on the blade, which is enabled by the cooperation between the inwardly directed oblong hole 8 and the eccentric disc 17, which then for 35 the adjustment of the member 4 becomes turned back in the requisite degree.

The device described has also the advantage, that the edge protecting member will be particularly firmly secured to the 40 knife-blade in the proper position to the edge.

Though I have here above spoken about the hole 6 in the blade as the hole, through which the member 4 can be withdrawn I 45 want to explain, that I do not wish to limit myself to exactly such an arrangement, but the scope of this invention includes also a reverse arrangement of the holes 6 and 8, so, that the screw head 10 can be placed in 50 position through the hole 6 and the member 4 removed by means of the hole 8.

What I claim is:

1. A protecting device for the edge of butchers' knives comprising a protecting

member provided on the knife-blade, said member held in proper position upon the knife-blade by means of a pin passing through holes in the knife-blade as well as in the edge protecting member, either of said holes having such a shape in relation 60 to the pin, that when the edge protecting member is swung about the pin out of its operative position for the sharpening of the knife-blade, said pin remains stationary 65 in relation to the one of said members but is revolved in relation to the opposite member, and said pin having a head, which bears against the last mentioned member, and has such a shape and size in relation 70 to the hole in said member, that when the edge protecting member is swung out from its operative position to a certain angle to the knife-blade, said pin head can pass through said hole for the purpose to enable 75 the removing of the edge protecting member from the knife-blade.

2. A protecting device for the edge of butchers' knives comprising an edge protecting member attached to the blade of the knife by means of a pin passing through 80 holes in said member and blade, a handle for the knife, a spring provided adjacent to said handle, and said spring adapted to retain the one end of said protecting member when in operative position.

3. A protecting device for the edge of butchers' knives comprising an edge protecting member attached to the blade of the knife by means of a pin passing through 85 oblong holes in said blade and edge protecting member, a handle for the knife, a spring provided adjacent to said handle and cooperating with the adjacent end of said edge protecting member, so as to hold said end in position, said end bearing against 90 a rotatable eccentric, and said oblong holes provided such, that by the rotation of said disc and the displacement of said protecting member along either of said holes, said protecting member is adjusted to the proper distance from the edge of the knife.

In testimony whereof I have affixed my signature in the presence of two witnesses.

FRITIOF CORNELIUS HAMMAR.

Witnesses:

JAN FRITIOF,
J. SORENSEN.
